UNITED STATES PATENT OFFICE.

KATHARINE C. MUNSON, OF WINTHROP, MASSACHUSETTS.

BERTH FOR VESSELS.

SPECIFICATION forming part of Letters Patent No. 431,385, dated July 1, 1890.

Application filed July 30, 1887. Renewed November 11, 1889. Serial No. 329,856. (No model.)

To all whom it may concern:

Be it known that I, KATHARINE C. MUNSON, of Winthrop, in the county of Suffolk and State of Massachusetts, have invented certain new and useful Improvements in Berths for Vessels, of which the following, taken in connection with the accompanying drawings, is a specification.

The object of this invention is to provide for the use of invalids and persons in delicate health an improved berth for steamships and other water-craft, and to furnish the same with a variety of attachments and conveniences which will tend to alleviate the discomforts of a sea voyage.

The various devices which are herein set forth may be employed in the same room, and are represented as applied to one or the other of two parallel berths mounted on one frame.

My improvements are illustrated in the drawings, and are hereinafter described, and particularly referred to in the appended claims. I design to include in the present patent improvements especially adapted to promote the comfort of passengers in case of sickness.

In the drawings, Figure 1 is a front elevation of the berth-frame with its two berths and canopy complete. Fig. 2 is a rear view showing the lower berth and various attachments to the frame. Fig. 3 is a longitudinal central vertical section seen from the front. Fig. 4 is a vertical section taken on line *y y* of Fig. 2 and looking toward the foot of the berths. Figs. 5 and 6 are details of the adjustable bearings.

The berth-frame is represented as suspended in such a manner that it will swing freely to compensate for the rolling motions of the vessel in stormy weather, so that the berths will not be materially tipped from side to side and the passenger's strength exhausted in the mere effort to remain in the berth.

Without limiting myself in the matter of suspension apparatus or laying claim to the particular form shown, I express a preference for the rolling bearings illustrated, in which a cylindrical hub *a*, attached to the wall or partition, forms a firm support for a series of rollers mounted in an annular bracket *b* on the end of the berth-frame. These supporting-trunnions are represented as mounted on

slides *c*, working in grooved ways *d*, fixed to the walls of the room, so that the whole apparatus may be drawn out from the rear wall 55 and held in position to swing freely, or may be pushed back and held firmly.

The berth-frame supports the lower berth A, the upper berth B, and a canopy C over the latter. Curtains D, supported by rods E, 60 inclose each berth separately, so as to cut off the sight of the walls of the room, which move relatively to the berths. The curtains conceal this movement, and thus tend to mitigate sea-sickness, besides giving privacy in 65 either berth when desired.

At the back side of the lower berth I provide a sliding upholstered back-support *f*, with a folding arm *G* at each side thereof, and along the front of said berth, near the floor, I 70 place a long horizontal step or foot-rest *H*, preferably supported on brackets hinged to the front of the berth, so as to turn down for use or to turn up and form a panel along the front of the berth. With these devices in 75 position the berth or bed is readily convertible into an arm-chair, in which one may sit at ease with the same freedom from discomfort because of the vessel's rolling which the berth itself afforded. The foot-rest is elongated and the chair-back movable longitudinally on ways formed by the rear side rails of the upper and lower berths, and hence the chair, made up as stated, may be located at desired points. I furnish a fine plush spread 85 for the top of the bed, corresponding in color with the upholstering of the chair-back. This gives to the structure, as a whole, the general aspect of a sofa.

The back-support *F* is a shallow closet or 90 locker with shelves or compartments for medicines and the like. The upholstered face *F'* of this locker is a sliding door to cover or inclose these compartments. The arms *G* are pivoted to the edges of the partitioned back portion *F*, and when extended forward they hold the upholstered face of the device in place, so that both parts slide together, but when either arm is turned up vertically the front or upholstered face may slide 95 edgewise and expose the contents of the compartments. When both arms are turned up, this face portion *F'* may move away to either side independently of the sliding movement 100.

of the main portion of the back. The arms G are peculiar. The base portion is pivoted to the back to turn up, as stated, and it folds down against a stop g. The upholstered arm-rest is hinged to the upper edge of this base portion to fold inwardly toward the opposite arm when in position for use. These arm-rests turn up edgewise on their hinges before the entire arm is turned up vertically on its pivot.

In one portion of the sliding back-support F, I have provided two faucets f, Fig. 4, connected by flexible tubes e with hot and cold water supply pipes of the vessel, so that either hot or cold water may be drawn, when desired, for any required use. These are wholly concealed by the upholstered face of the back when in position. I also furnish a portable and collapsible bath-tub t, which may be placed upon the lower berth and supplied with water from the faucets or otherwise, which will not be spilled when properly-suspended berths are employed. A short section of rubber tubing r may run from the faucets to the tub and to the closet-seat, to be described. In addition to this the berth is provided with a press-button p, connected by a flexible wire with a call-bell or other signal, so that when required an attendant or officer may be summoned.

A feature of this invention is a stool, commode, or water-closet seat directly connected with the berths. The lower berth is furnished with a spring or hair mattress, of which a small section I, near the foot of the bed, is made removable, so as to expose beneath it a closet-seat K, of usual form, on which the removable section rests. Beneath this is the receiving jar or vessel J with a tapering sleeve j leading thereto. Suitable provision is made for removing this vessel for emptying, preferably by hinging a part of the front of the berth as at k. A thick ring of rubber packing may be interposed between the seat and the vessel J, and the bottom of the removable section I may be covered with like material. A suitable disinfectant will be provided. Water for cleansing or flushing may be supplied from the faucets f through rubber tubes r.

For convenience of access to the seat the lower sheet of the berth A may be furnished with a flap M, which will turn up to expose the removable section of the bed and when turned down may be fastened to the foot portion of the sheet by buttons or otherwise.

The adjustability of the back F enables it to be placed opposite to the seat K, when desired, thereby affording a support which to invalids or the infirm is of great value. The separately folding arms G give a temporary support at each side, and may be turned up out of the way or turned down, as required.

I furnish the upper berth with a urinal O, located at the backside of the berth and about midway of its length. It is furnished at the top with a suitable cover o. A tube P extends downwardly to the jar or vessel J' be-

neath berth A. The parts may be flushed with a liquid disinfectant, when desired, by means of a bottle-and-bulb syringe or like devices. The receiving-vessels J will be held in small compartments or set in shallow sockets, so as not to be displaced. Other compartments Q at either side of these vessels may receive shoes or other articles, all being concealed by the door k, which is below the foot-rest H.

The vessel J' is shown resting upon a hinged tray q, which yields downwardly as the vessel becomes partly filled, and by such movement bears down upon a foot connected by a lever l with a signal-rod s, extending up to the upper berth, so that the occupant may be warned by the position of said rod or by a bell struck by it before the vessel overflows. (See Figs. 1, 2, and 4.) The spring s' gives the yielding support to the tray q.

At the foot of the berth-frame, in the angle beneath the upper berth, I have provided a small cupboard W, designed for a hat-box and capable of receiving through an end-door a lady's bonnet or the like, thus utilizing this portion of the space. The face of this box may be provided with a mirror Y, if desired. Below this small cupboard is a transverse shelf Z, preferably upholstered to correspond with the berth-cover, and adapted to support food, dishes, clock, or any small articles within reach from the berth.

At the head of the berth A, I provide an adjustable head-rest R, consisting of a border or frame extending across the head of the berth and along each side of it for fifteen or twenty inches, pivoted at its ends to the inner faces of the side rails of the berth and having a stout fabric stretched across and secured to such frame. At each side of the berth is a cord S, running through a ring in the bottom of the upper berth and connected to the head of this frame, so that by drawing on either cord the rest R will be raised obliquely on its pivots to the desired angle, and held by a ratchet and pawl or any suitable means. When dropped down the frame rests close to the edges of the berth and the fabric lies flat across the mattress over the lower sheet. I am not aware of any similar device as a permanent attachment to a suspended berth prior to my invention.

The rear view, Fig. 2, represents my devices for locking the berth-frame to the partitions. Two bolts h, sliding horizontally in bearings i, are worked by a pivoted lever m, which extends up to the upper berth, so that from either berth said bolts may be thrown to engage with their sockets in the walls or to be released therefrom, so as to prevent or permit free suspension, as desired. The lever is provided with suitable catches to hold it in either position.

A folding step n, similar to the folding arm G, is attached to the foot of the frame for more convenient access to the upper berth. (See Figs. 1 and 4.)

I mount a swinging table T on a bent arm

u, working in a vertical socket U, near the head of the berth, so that the table may be moved on its pivot to and over the front of the berth or away to the wall. The table 5 may support food or medicine; but I have especially designed it as a cover for a vomiting-pan attached to the front of the berth in case of sickness. In connection with this I provide a pendent head-support or flexible 10 sling V, hanging from a hook in the upper-berth bottom and adapted to slip over the forehead of the invalid and give a much-needed support to the head in vomiting. The sling is removable or may be drawn aside entirely 15 out of the way when not required for use. (See Fig. 2.)

I claim as my invention—

1. The combination of a sleeping-berth with a back-support mounted upon the rear rail of 20 the berth-frame, leaving the berth unobstructed, and with arms pivoted to such support, whereby the berth is convertible into an arm-chair or sofa, substantially as set forth.

2. The combination of a sleeping-berth with 25 a back-support made adjustable along the rear side thereof to different positions and provided with pivoted arms, substantially as and for the purpose set forth.

3. The combination of a sleeping-berth with 30 a longitudinally-adjustable back therefor, provided with internal compartments and with a sliding front or cover for such compartments, substantially as set forth.

4. The combination of a sleeping-berth with 35 a longitudinally-adjustable back therefor, having pivoted arms, as described, and with a step or foot-rest applied to the front of said berth, for the purpose set forth.

5. The combination of a sleeping-berth with 40 a back therefor arranged to slide along the rear rail of the berth, and with arms pivoted to the edges of such back and provided with arm-rests hinged to fold inwardly on said arms, substantially as set forth.

45 6. The combination of a sleeping-berth provided with a spring or stuffed mattress with a stool or closet-seat K and a permanent sleeve j, and removable jar or pan J below it, all located within the berth-frame, and with 50 a removable section of such mattress, serving to cover and conceal such seat, substantially as set forth.

55 7. The combination of a sleeping-berth having a stool or closet-seat and jar located within it with a mattress having a removable section, with wooden bottom constituting a cover over said seat or jar, and an adjustable back-support, which may be placed opposite said seat, substantially as set forth.

60 8. The combination, with a pair of suspended sleeping-berths, of a urinal fixed with-

in the frame of the upper berth, a discharge-pipe leading therefrom to a concealed receptacle in the frame of the lower berth, and a cover for said urinal, substantially as set 65 forth.

9. The combination of a suspended berth-frame with lower and upper berths A and B and a canopy C, with curtain-supports along its edge, and with curtains connected to said 70 parts to inclose the berths when desired, substantially as set forth.

10. The combination of a suspended berth having a chambered longitudinally-adjustable back-support with faucets f, fixed within 75 such chamber, and with flexible tubes connecting said faucets with a source of water-supply, substantially as set forth.

11. The combination of a suspended berth-frame and two berths mounted thereon with 80 an adjustable head-rest R, having its frame connected pivotally to the edges of the lower berth, and provided with a hoisting-cord running through a ring beneath the upper berth, whereby the occupant of the lower berth may 85 elevate the head-rest obliquely, substantially as set forth.

12. The combination of a suspended berth, with a table T, swinging horizontally on an arm pivoted to the front of the berth-frame, 90 substantially as set forth.

13. The combination of a suspended berth-frame and the upper and lower berths upon it with a pivoted locking-lever m, extending within reach from both berths, and two sliding bolts h, adapted to secure said frame at its lower portion to the walls of the room at each end of the berths or to disengage it, as desired, substantially as set forth. 95

14. The combination, with a suspended 100 berth, of a flexible depending sling V, secured to the supporting-frame above such berth, and adapted to serve as a temporary support for the head of an invalid, substantially as set forth. 105

15. The combination, with a pair of suspended sleeping-berths placed one above the other, and with a urinal fixed within the upper-berth frame, of a pipe leading thence to a receiving-vessel inclosed beneath the lower 110 berth, a yielding platform on which said vessel stands, and a signal apparatus connected with said platform and actuated therefrom, substantially as set forth.

In testimony whereof I have signed my 115 name to this specification, in the presence of two subscribing witnesses, on this 28th day of May, A. D. 1887.

KATHARINE C. MUNSON.
